CLAIM

The ornamental design for a carpenter's gauge for installing trim around doors and windows, as shown and described.

DESCRIPTION

FIG. 1 is a front elevational view of a carpenter's gauge for installing trim around doors and windows showing my new design;

FIG. 2 is a rear elevational view;

FIG. 3 is a top plan view;

FIG. 4 is a bottom plan view;

FIG. 5 is a left side elevational view;

FIG. 6 is a right side elevational view;

FIG. 7 is a top, front, and right side perspective view thereof; and

FIG. 8 is a top, front, and right side perspective view of another embodiment of FIGS. 1-7.

FIG.1

FIG.2

FIG.3

FIG.4

FIG.5

FIG.7

FIG.6

FIG. 8
